UNITED STATES PATENT OFFICE.

WOLDEMAR KIWULL, OF BERLIN-HALENSEE, AND WALTHER KOENIGER, OF BERLIN, GERMANY.

MEANS AND METHOD FOR RAISING AND SALVAGING SHIPS AND OTHER SUNKEN OBJECTS.

Application filed March 14, 1925. Serial No. 15,456.

To all whom it may concern:

Be it known that we, WOLDEMAR KIWULL, a Lettish citizen, and WALTHER KOENIGER, a German citizen, residing, respectively, at 5 117 Kurfurstendamm, Berlin-Halensee, Germany, and 44 Landhausstrasse, Berlin, Germany, have invented certain new and useful Improvements in Means and Methods for Raising and Salvaging Ships and Other 10 Sunken Objects, of which the following is a specification.

The method of raising sunken ships by employing the formation of ice to form a complete coating or to form ice blocks in 15 spaces in the ship with subsequent withdrawal of the water to produce buoyancy is already known and the present invention relates to certain improvements in the ice formation for the purpose of raising or salvaging sunken ships and other sunken objects which enable large quantities of ice to be readily formed at the points required, so that the ice formation can be utilized 20 without coating the whole ship or sunken 25 object with ice.

According to this invention the formation of ice is effected through the direct cooling by the refrigerating means of the metal of the ship or body to be raised, so as to maintain the metal at the desired points at a 30 lower temperature than that of the surrounding ice which forms upon the cooled metal and remains attached to it. It has been found that to attach securely a layer 35 or body of ice to the metal of a ship, in order, for example, to close openings in the ship so that the interior space may be rendered water-tight and allow buoyancy to be obtained by the removal of the water, it 40 is essential that the metal itself should be cooled below the temperature of the ice which is forming around it. If ice is formed externally to the metal surfaces to which it is to be attached and is merely allowed to 45 meet the metal no proper adhesion is possible and openings in the vessel cannot be hermetically closed by such ice formation, whereas if the ice itself starts to form at the surface of the metal thorough adhesion is obtained between the ice and the metal surface. 50

To form an ice layer to cover any opening in the ship it may be desired to close a mat comprising cooling means may be employed, which mat is frozen to the ship and made

into a rigid body by the formation of ice 55 which adheres to the metal surface owing to the supercooling of this surface. Another means for effecting the formation of an ice layer in a suitable position within an enclosed space in the ship is to effect freezing by a highly cooled liquid of lower specific gravity than water, the liquid rising in the space and forming below it a solid ice layer, below which an air space may be 60 formed by forcing out the water. The highly cooled liquid will, of course, also meet the metal surface of the ship, for example, a metal deck, which will form ice by cooling of the water in contact. Lifting caissons 65 can also be attached to the ship by formation of connecting ice layers produced by the supercooling of the metallic surfaces.

In order that the said invention may be clearly understood and readily carried into effect, the same will now be described more 70 fully with reference to the accompanying drawings, in which:

Figure 1 illustrates diagrammatically the formation of ice when an iron mass or body is supercooled by the cooling medium.

Figures 2 and 3 illustrate a method of securing a lifting pontoon to the upper part or deck of a ship.

Figure 4 shows the attachment of rigid vertical pontoons to the sides of the ship.

Figure 5 is a cross section through a sunken and stranded ship illustrating the use of a refrigerating liquid floating on the water and coming into contact with the metal of the ship; and

Figure 6 illustrates a method of forming ice on and below the deck of a sunken ship.

In carrying out the method illustrated in Figure 1, the cooling element 1 forming part of the refrigerating plant, which may be of any convenient type, is in direct contact with the metal 2, which may be the ship's skin deck or plates with cross girders 3, and the ice 4 forms over the cooling element and also along the metal as indicated, the arrows showing the manner in which the cold distributes itself through the metal so as to cool the water in contact with its surface over a considerable range instead of allowing the ice to be formed merely around the cooling element.

Vessels filled with a freezing mixture or with liquid air or cooled by a supply of

carbonic acid, could be lowered for the purpose of freezing in or on to the ship as indicated in Figures 2 and 3. These tanks 4 filled with liquid air or cooled by carbonic acid escaping from the bottle 5 must, unlike the ordinary storage vessels for liquid air, be such as to allow of an exchange of cold, which can be regulated and localized. If in such a tank 4 the exchange of cold is to take place only through the bottom, the tank is enclosed laterally with insulating layers 6 and air layers 7 arranged as required for the purpose of regulating or preventing lateral exchange of cold. The exchange of cold with the ship's hull taking place through the bottom of the said tank 4 can be effected by direct contact of the bottom of the ship's hull. Regulated insulating layers (such as cork plates) 8 may be provided to limit the range of contact.

The exchange of cold from the sunken tanks 4 effects a freezing in of the hatches, upper structures, etc., and completely closes the ship in a water-tight manner by the layer of ice. The intense cold of the liquid gases can also be utilized for freezing the tanks to the outer plating 2 of the ship and ensuring a firm connection between the tank 4 and the ship by the formation of ice as shown. On the frozen on tank is shown lifting means 10 (pontoons or balloons) so that the gases of evaporation would pass into the lifting devices in order to provide the buoyancy required for raising. In Figure 2 the pontoon is shown of flexible or balloon type secured to the tank by ropes 11 while in Figure 3 a rigid caisson 10 of rectangular shape is shown.

In Figure 4 two vertical caissons 12, 12 are shown, one at each side of the ship 13, which caissons are rigidly connected to the hull of the ship by an ice layer 14, shown at one side of the drawing only, the ice layer extending inside the skin of the hull so that the latter is firmly attached to the ice, the hull being supercooled. To avoid freezing of the internal water in the caisson 12 an insulating layer 15 may be provided at the portions of the caisson at which the ice layer 14 is to be produced. The insulating layer 15 may be in the form of an air space used for balancing the dead weight of the caisson. The refrigerating plant 16 required for the ice production is shown diagrammatically mounted on the upper side of the caisson, but this could, of course, be arranged inside and the cooling water 17 required for the refrigerating machine 16 could also be taken direct from the caisson through the tube system 18 enabling the caisson to be emptied through the apparatus 16 simultaneously with the production of the ice layer 14. The freezing element of the plant is indicated at 19.

65 A further method of ice formation is

illustrated in Figure 5, which indicates in a diagrammatic manner a section of a sunken vessel. In this case the cooling liquid, which is of lower specific gravity than the water, is directly introduced into the ship 70 and rises through the water in direct contact with it, but without mixing. In the illustration given in Figure 5 the ship is shown with a leakage hole 20 in the bottom in such a position as to be quite inaccessible. Under such circumstances a layer of cooled oil 21 can be poured into the space in the vessel, being retained in the vessel by the plates 22 and 23 and bulkheads 24, the oil spreading uniformly over the water surface, cooling also the metal surfaces in contact with it, and forming a layer of ice 25 under the oil layer. The thickness of the ice layer 25, into which parts of the ship's construction and other strengthening members can be frozen in, may be made sufficient to allow the water to be discharged from the space 26 below the ice layer 25, the water being expelled through the leak 20 in the bottom of the ship. The ship can by this means be sufficiently lightened to float.

Figure 6 illustrates a method of ice formation in which the upper deck of a foundered ship lying on her beam ends is cooled by a refrigerating plant indicated at 27, causing the iron plating of the deck 28 to be covered with an ice layer 29. The deck 28 is usually covered with wooden planks 30 which insulate the cooled iron at the outer side. The inner side of the deck is provided with iron beams 31 which distribute the cold effectively and the inner deck covering 32 retains the cooled water under the plating of the deck until it is converted into ice 33. The deck openings, hatchways and any openings in the outer casing are stopped by the formation of ice layers 34, produced if required by one of the methods already described. When the deck 28 is completely frozen the expulsion of water from the ship's hull can be effected by means of compressed air, the internal pressure during the expulsion of the water being resisted effectively by the frozen deck.

In all cases where the ice formation is obtained on the lines above described cooling of the iron parts of the ship's hull is effected and consequently there is a contraction which facilitates the detachment of the ship from the sea bottom, especially in cases where the ship may be partly covered with sand or mud. Owing to the large mass of the ice produced and the low temperature to which the parts of the vessel itself are cooled the ice melts very slowly during the raising of the ship or in the event of any unavoidable interruption of the work, so that the ship can be towed without any special preparation as soon as it is raised and if the work is interrupted the renewed

formation of ice is facilitated by the cold retained by the vessel.

What we claim and desire to secure by Letters Patent of the United States is:—

- 5 1. A system of salvaging sunken ships and other bodies by the aid of the artificial formation of ice in contact with the bodies, which consists in applying the refrigerating means directly to the metal of the ship or
- 10 body to be raised so as to maintain the metal at the required position at a lower temperature than that of the surrounding ice which forms upon the cooled metal and remains attached to it.
- 15 2. In a system of salvaging sunken ships and other bodies as in claim 1, regulating and localizing the exchange of cold between the metal and the surrounding ice by the provision of heat insulating means.
- 20 3. In a system of raising sunken ships and other bodies as in claim 1, effecting the attachment of raising means to the sunken body by the formation of the ice which is attached both to the raising means and the
- 25 metal of the sunken body.
- 30 4. Means for salvaging sunken ships and other bodies by the aid of the artificial formation of ice, comprising a flexible mat adapted to be placed over an aperture in the sunken body, means for cooling the metal of the sunken body below the temperature of the ice formed upon it by said cooling, and cooling means applied to the flexible mat whereby the mat is formed into a rigid
- 35 closing member attached to the body by the formation of the ice through and around the mat.
- 40 5. Means for salvaging sunken ships and other bodies by the aid of the artificial formation of ice, comprising a mat com-

posed of a network of tubular cooling elements, means for supplying a cooling liquid to the said tubular cooling elements and means for cooling the metal of the sunken body below the temperature of the ice which forms upon the body and upon the flexible network, so as to make the latter into a rigid member attached to the body by the ice which is formed.

6. In salvaging means as in claim 5, an enclosing layer of fibrous material surrounding the network of tubular cooling elements.

7. In salvaging means as in claim 5, an enclosing layer of fabric surrounding the network of tubular cooling elements.

8. Means for salvaging sunken ships and other bodies by the aid of the artificial formation of ice, comprising a flexible mat with double sides and means for supplying a cooling medium between the two sides of the mat to cause the formation of ice over the surface of the mat.

9. In salvaging means as in claim 8, heat insulating means provided over a portion of the said mat whereby the formation of ice is limited to a selected part of the mat.

10. In a system of raising sunken ships and other bodies by the aid of the artificial formation of ice, a method of cooling the metal portions of the ship or body and for the formation of the ice which consists in adding to the water within an enclosed space in the body a highly cooled liquid of lower specific gravity than water, which liquid rises within the space against the metal surface and also forms below it a solid ice layer.

WOLDEMAR KIWULL.
WALTHER KOENIGER.
